FIG. 8

FIG. 9

FIG. 1 is a perspective view of a single convertible table tennis table and shelf unit showing our new design with the table element pivoted into the upright position;

FIG. 2 is a front elevational view of the table unit;

FIG. 3 is a rear elevational view thereof;

FIG. 4 is a plan view thereof;

FIG. 5 is a bottom view thereof;

FIG. 6 is a side elevational view thereof, the other side being substantially a mirror image thereof;

FIG. 7 is a perspective view to reduced scale of the tennis table unit with the table element pivoted into horizontal position to provide a full length table tennis table when placed against a second like unit;

FIG. 8 is a view similar to FIG. 2 showing another embodiment of the design with vertical spacers extending between the shelves; and

FIG. 9 is a similar view of a still another embodiment wherein sliding doors are provided to enclose the space between the shelves.

We claim:

An ornamental design for a convertible table tennis table and shelf unit, as shown and described.
